F. E. BROKAW

SELF ADJUSTING CLAMP FOR CARD TABLE COVERS

Filed Nov. 24, 1923

Inventor:
Frank E. Brokaw,
Joseph W. Harris
Atty.

UNITED STATES PATENT OFFICE.

FRANK E. BROKAW, OF SCHOFIELD BARRACKS, TERRITORY OF HAWAII.

SELF-ADJUSTING CLAMP FOR CARD-TABLE COVERS.

Application filed November 24, 1923. Serial No. 676,847.

To all whom it may concern:

Be it known that I, FRANK E. BROKAW, a citizen of the United States, and residing at Schofield Barracks, in the county of Oahu, 5 and Territory of Hawaii, have invented certain new and useful Improvements in Self-Adjusting Clamps for Card-Table Covers, of which the following is a specification.

This invention relates to detachable 10 clamps for table covers for card tables by which the cover may be temporarily securely held in place, and may be readily and quickly applied and removed.

An object of the invention to provide a 15 means by which a removable table cloth or similar cover may be readily secured, temporarily to a card table, and be as quickly removed;

A further object is to provide a means for 20 holding the cloth that will not require passing pins, or other securing means, through the cloth;

A further object is to provide a means 25 that is ornamental in appearance, and that will not scratch the table, nor catch hold of the clothing of a person sitting at the table;

A further object is to provide suitable 30 ornamental handles by which the clamps may be attached and detached;

Further objects will appear on reading the specification.

In the drawings:

Figure 1 is a front view of a pair of clamps, showing the plates or faces of ornamental design, and the attached elastic means connecting the plates or faces, also the attached handles by means of which the clamp may be applied to the table;

Fig. 2 is a side view of the same, showing 40 the bent tang at the lower extremity of the plate or face, and the pressed-out loop to which the handle is secured and also showing the broad hooked end which engages the edge of the cloth and the rim or molding of the card table;

Fig. 3 is a view of a section of a table, showing one of the clamps holding the cloth in place;

Figs. 4 and 5 are views in perspective of 50 a corner of a card table, with the clamps in place, and showing the elastic spring stretched behind the table leg;

Fig. 6 is a view in perspective of a clamp 55 showing the pressed-out loop with openings above and below, through which a link passes to carry a handle, and also the bent-

out lower tang by which the elastic member is attached;

Figs. 7, 8, 9, 10, and 11 are a section and front views of different ornamental designs 60 of clamps.

Fig. 12 is a modification showing other ways of attaching a handle and the spring.

In Figs. 1 and 6, the clamp is shown to consist of a pair of clamping plates or face 65 pieces 1, which may be of any suitable material such as sheet metal, having a broad hooked top, 2, Fig. 6, and shown in dotted lines in Fig. 1, and a bent-out lower end or tang, 3, to which an elastic member such as 70 a helical spring, or a piece of rubber, 4, is attached by a suitable link. In the body of the plate or face of the clamp 1, is a pressed-out portion, or loop, 6, with perforations 7 above and below, and through which a link 75 8 passes, the link supporting a suitable loosely connected ornamental handle, such as a tassel 9. While this handle 9 is shown linked through a loop, it may be loosely secured by any other suitable means, such as 80 by soldering or brazing a link 10 of a short length of chain 11 to the plate or face of the clamp, Fig. 12, the chain serving as the handle. The lower tang of the clamp may also have a link 12 soldered or brazed thereon, 85 the elastic spring 13 being attached thereto.

The inside surface of the plate 1 is smooth, or flush, there being no projections, or links, extending therefrom which may possibly scratch the side of the table, or become entangled in the table-cloth.

The plate or face may have any suitable shape, or design, for example as shown in Figs. 8 to 11 inclusive, the plates may represent the suits of a deck of cards. Private 95 coats of arms, or other heraldic devices, may also be used as designs for the plates.

Card tables as generally made, have a wood frame 16, Fig. 3, upon and within which is placed the table top 17; the frame 100 16 is provided with a deep groove 18, into which the edges of the table cover are pressed and secured. This construction leaves a groove, or depression all around the edge of the table, just inside the edge or molding of the frame. It is customary to round off the top edge of the frame, as shown in Fig. 3, and this rounded edge 20, together with the upper part of the groove 18, provides a support for the broad hook 2 of the clamp, and serves to firmly engage the 105 table cover 15.

In use, the table-cloth 15 is spread on the card table 16 and one of the plates of the clamps is pressed down on the edge of the table 16, the broad hook 2 pressing the cloth 5 along the groove adjoining the wood frame, as shown in Figs. 3 and 5. The other plate is then grasped by its handle 9 and is passed behind the table leg, Fig. 4, and the elastic member 4 stretched until the plate 10 is placed on the other side of the table, as shown in Fig. 5. The operation is repeated at all of the corners of the table. The broad hooks 2 of the clamps provide a large surface for engaging the table cloth, without 15 risk of tearing or otherwise disfiguring any part of the table or cloth.

I claim:

1. In a detachable clamp for table covers, a clamping plate, said plate provided with 20 a broad hooked end, said plate having a flush inner surface, a bent out tang at the lower end of said plate, an elastic member attached to said tang, and a loose handle secured to the face of said plate.
2. In a detachable clamp for table covers, a clamping plate, said plate provided with a broad hooked end, said plate having a flush inner surface, perforations in said plate, the metallic web between said perfora- 25

tions being pressed out into a loop, a link 30 engaging said loop, and a handle attached to said link.

3. In a detachable clamp for table covers, a clamping plate, said plate provided with a broad hooked end, said plate having a flush inner surface, perforations in said plate, the metallic web between said perforations being pressed out into a loop, a handle suspended from said loop, the lower end of said plate bent outward, and an elastic member 35 suspended from said end.

4. In a detachable clamp for table covers, a pair of clamping plates, an elastic member connecting said clamping plates, said plates having inner surfaces free from projections, and a loosely attached handle on 40 each of said plates.

5. In a detachable clamp for table covers, a pair of clamping plates, a broad hooked end on each of said plates, said plates joined 45 together by an elastic member, said plates having inner surfaces free from projections, perforations in each of said plates, the metallic web between said perforations being pressed out into a loop and a handle suspended from said loop.

In testimony whereof I affix my signature.
FRANK E. BROKAW.
